DISPLAY DEVICE

Albert W. Janke, Iowa Falls, Iowa, assignor to
L. C. Perkins, Belmond, Iowa

Application February 18, 1939, Serial No. 257,190

2 Claims. (Cl. 211—89)

This invention relates to display devices, and its general object is to provide a device of that character in the form of a holder primarily designed for use in displaying merchandise, especially pieces of candy, nuts and other small articles generally packaged for sale in transparent bags or like containers, the holder including means to set up a gripping engagement with the bags for holding them in an attractive manner and so that any one or more bags can be readily removed from the device without disturbing the others, yet casual removal is practically impossible.

A further object is to provide a display device that is neat and attractive in appearance, can be readily secured in position for use, is simple in construction, inexpensive to manufacture, and extremely efficient in use, operation and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a fragmentary perspective view of the display device which forms the subject matter of the present invention.

Figure 2 is a side view thereof partly in section, with bags of articles clamped between certain convolutions of the coil spring, to illustrate the manner of displaying the same.

Figure 3 is a top plan view, showing a bag in dotted lines.

Figure 4 is a fragmentary vertical sectional view taken through the upper end portion of the device.

Figure 5 is a fragmentary vertical sectional view taken through an intermediate portion thereof.

Referring to the drawing in detail, it will be noted that my display device includes an elongated relatively narrow body in the form of a strip channel bar in that the body is made up of a strip like rear wall 1 having relatively narrow lateral flanges 2 formed on the side edges thereof, and extending forwardly therefrom for disposal in parallelism with each other, as clearly shown in Figure 3. The flanges are of a length substantially co-extensive with that of the wall 1, but terminate adjacent to the ends thereof and the ends are rounded to provide attaching ears 3

having openings therein to receive suitable securing means, such as screws or the like for securing the device preferably in a vertical position, to suitable supporting means, such as for instance to the front face of a partition member of shelves in a grocery store or the like.

Mounted in the ends of the channel bar between the flanges thereof are substantially U-shaped members 4 having the ends of the arms thereof extending through slots at the juncture of the rear wall with the flanges and the ends of the arms are bent against the rear face of the rear wall for the purpose of cooperating with tongues 5 formed on the ends of the flanges and bent in clamping engagement with the inner faces of the arms of the U-shaped member, for securing the latter to the channel bar.

Disposed within the channel bar is a closely wound coiled spring 6 of a diameter to extend forwardly a considerable distance beyond the flanges 2. The spring is secured in place by lugs 7 formed on the inner edges of the arms of the U-shaped members and extending inwardly therefrom for disposal between certain end convolutions of the springs, as best shown in Figure 4, and cooperating with the lugs 7 for the purpose set forth, are substantially triangular shaped tongues 8 struck from the rear wall 1 and bent into clamping engagement with certain intermediate convolutions, as best shown in Figures 30 and 5.

From the above description and disclosure of the drawing, it will be obvious that I have provided a simple and inexpensive display device to be attached preferably into a vertical position for use, as suggested in Figure 2, and that the convolutions of the coil springs cooperate with each other for receiving between the same, one of the ends of bags or the like, partially filled with small articles of merchandise such as pieces of candy, nuts, etc., commonly packaged for sale in bags of the type shown. It will be further obvious that the convolutions set up a clamping engagement with the bags and that the latter assume a position for disposal in superimposed row formation, thereby presenting a neat and attractive appearance which tends to induce the sale of the merchandise, as will be apparent.

It is thought from the foregoing description that the advantages and novel features of the invention will be readily apparent.

It is to be understood that changes may be made in the construction and in the combination and arrangement of the several parts, provided

that such changes fall within the scope of the appended claims.

What I claim is:

- 5 1. A display device comprising a relatively narrow elongated body in the form of a channel bar, a closely wound coil spring extending along the length of the channel bar and seated therein for disposal forwardly therefrom, substantially U-shaped members secured to the ends of the channel bar for enclosing the ends of the coiled spring, means formed on the U-shaped members and received between certain end convolutions of the spring for securing the latter with respect to the bar, the convolutions of the spring cooperating with each other to provide clamping means for articles to be displayed, and attaching means on the body for receiving suitable means for securing the device in use.
- 10 15 2. A display device comprising a relatively nar-

row elongated body in the form of a channel bar, a closely woven coil spring extending along the length of the channel bar and seated therein for disposal forwardly therefrom, substantially U-shaped members secured to the ends of the channel bar for enclosing the ends of the coil spring, lugs extending inwardly from the U-shaped members and received between certain end convolutions of the spring, tongues struck from the channel bar and received between certain intermediate convolutions of the spring for cooperation with the lugs for securing the spring in place, the convolutions of the springs cooperating with each other to provide clamping means for articles to be displayed, and ears formed on the ends of the channel bar and having openings therein for receiving suitable means for securing the device in use.

ALBERT W. JANKE.

CERTIFICATE OF CORRECTION.

Patent No. 2,185,086.

December 26, 1939.

ALBERT W. JANKE.

It is hereby certified that the above numbered patent was erroneously issued to "L. C. Perkins" as assignee of the entire interest therein, whereas said patent should have been issued to the inventor Albert W. Janke and L. C. Perkins as assignee of one-half interest therein, as shown by the record of assignments in this office; and that the said Letters Patent should be read with this correction therein that the same may conform to the record of the case in the Patent Office.

Signed and sealed this 25th day of June, A. D. 1940.

(Seal)

Henry Van Arsdale,
Acting Commissioner of Patents.
